UNITED STATES PATENT OFFICE.

WILLIAM EDWARDS HUNT, OF SILVER CITY, NEW MEXICO.

REPRODUCER FOR PHONOGRAHS.

1,410,679.

Specification of Letters Patent. Patented Mar. 28, 1922.

Application filed April 1, 1919. Serial No. 286,741.

To all whom it may concern:

Be it known that I, WILLIAM E. HUNT, a citizen of the United States, and a resident of Silver City, in the county of Grant and State of New Mexico, have invented 5 certain new and useful Improvements in Reproducers for Phonographs, of which the following is a specification.

My invention relates to improvements in 10 reproducers for phonographs or other sound reproducing devices, and it consists in the combinations, constructions and arrangements herein described and claimed.

An object of my invention is to provide 15 a reproducer by means of which a perfectly clear, distinct loud and natural tone is secured, and in which the so-called mechanical noises and the nasal twang are eliminated.

A further object of my invention is to 20 provide a device in which the lapping of sounds caused by echoes is obviated, and in which the loudness of sound is increased.

A further object of my invention is to 25 provide a novel form of diaphragm which is divided into sections in such a manner as to insure clear, loud, and natural tones.

A further object of my invention is to 30 provide a novel means for holding the needle in the stylus bar.

Other objects and advantages will appear 35 in the following specification, and the novel features of the invention will be particularly pointed out in the appended claims.

My invention is illustrated in the accompanying drawings, forming part of this 40 application, in which:

Figure 1 is a section through the reproducer;

Figure 2 is a face view thereof; a portion being broken away;

Figure 3 is a section along the line 3—3 of Figure 1, looking in the direction of the arrows;

Figure 4 is a face view of a modified form of the diaphragm;

Figure 5 is an enlarged section along the line 5—5 of Figure 4;

Figure 6 is a face view of another modified form of the diaphragm; and

Figure 7 is an enlarged sectional view along the line 7—7 of Figure 6.

Figure 8 is a detail view of the opposed quadrant shaped dampener.

In carrying out my invention I provide 55 a funnel-shaped body portion 1 of any suit-

able material whose sides are set at substantially 80° having at its small end an integral, cylindrical extension 2, adapted to fit over the small end of the tone arm of a 60 phonograph. The large end of the body portion 1 has a laterally extending inclined flange 3, whose inner face is inclined at substantially 10° from the rim of the funnel to approximately midway to the periphery 65 of said flange, and provided with a slightly raised annular rim 4. The rim 4 supports a ring 5, whose upper edge is rounded as shown at 6, this ring being undercut so as to hold the diaphragm in the manner here- 70 inafter described. In the form of the device shown in Figure 1, the diaphragm is shown as a dish-shaped membrane 7 whose edges are held between an upper and a lower rubber ring 8 and 9 respectively. The 75 ring 5 is secured to the flange 3 by means of screw bolts 10, the heads of these bolts being countersunk as shown in the drawings, and the ring 5 being drawn down tightly to clamp the diaphragm securely be- 80 tween the rubber rings 8 and 9.

By providing the body member of the reproducer with a funnel shaped opening and the inclined surface 3, approximately all of the sound waves from the diaphragm 85 will be thrown into the opening through the body member 1, either directly into the funnel extending therethrough or after one or more rebounds from the inclined surface 3. I am enabled to thus employ prac- 90 tically all of the sound waves set in motion by the diaphragm, without causing neutralization of said sound waves by the opposed phases thereof, as is common in reproducers as now constructed, and which results in 95 loss of intensity and clearness of tone, by the use in conjunction with such a dia- phragm and body member of dampening means to be hereinafter described.

The ring 5 is provided with lugs or ears 100 11 through which pivot pins 12 extend. These pivot pins support the vibrating arm 13, one end of which extends inwardly toward the center, is bent laterally, and is secured to the center of the diaphragm at 105 14. The opposite end of the arm is threaded as shown at 15, and is provided with slots 16, and also with a longitudinal bore (not shown) into which the stylus or needle 17 may enter. A nut 18 is provided 110 by means of which the needle may be clamped firmly in position, the slotted,

threaded portion being slightly sprung when the nut is turned to grip the needle securely.

Covering the end of the reproducer is a piece of cotton cloth 21, whose edges are secured to the outer, upper face of the ring 5. This cloth is fairly thick, or rather closely woven, and is provided with an eyelet 22 through which the vibrating arm 13 10 may extend.

From the foregoing description of the various parts of the device the operation thereof may be readily understood. The vibrations received when the stylus is traveling over the groove in the record (not shown) are transmitted to the diaphragm through the vibrating arm 13 and the latter is in turn caused to vibrate. The member 19 serves to absorb adverse vibrations set 15 up by the diaphragm body and reduces the sharpness and shrillness of the tone.

Furthermore by the provision of novel means whereby the sound waves which are not thrown directly into the opening of the 20 reproducer, are reflected so as to ultimately pass into said opening, the volume of the tone produced is increased and echoes are eliminated.

The particular material which I prefer to 25 use in making any of the diaphragms, i. e., the form shown in Figure 1, that shown in Figures 4 and 5, and that shown in Figures 6 and 7, is rawhide shaved to proper thinness and stiffened by wetting and drying, 30 and then lacquered to prevent the absorption of moisture. Such a coating of lacquer is shown at 24 in Fig. 5. By dividing the diaphragm into sections, practically independent portions of the diaphragm are provided which will vibrate independently, and 35 since one section will not control the vibration of the adjacent sections, they will all vibrate in unison, thereby causing the sound waves from all parts of the diaphragm to be 40 of the same phase, giving a loud, clear, and natural tone without the necessity of interposing an absorbing medium, as previously 45 described.

Instead of dividing the diaphragm, the 50 same effect may be produced by stiffening it in the manner set forth in Figures 6 and 7. This may be done in a number of ways, but preferably by the use of straws 25, set after the manner of the spokes of a wheel. The 55 diaphragm 7^b is made thinner than in the form shown in Figure 5 but the stiffening members 25, act as interrupters to the contrary vibrations of the opposed sections of the diaphragm, to cause all parts of the 60 latter to vibrate in unison.

While the reproducer is primarily designed to be used in connection with phonographs, it is applicable to any kind of sound reproducing, sound recording, or sound transmitting instrument, and is intended to 65 apply to any kind of talking machine or telephone now in common use.

I claim:

1. A reproducer, including in combination with a reproducer housing and diaphragm 70 associated therewith, of dampening means within said housing and spaced from said diaphragm, said dampening means including a piece of material presenting two opposed sections of a circle joined at the 75 center.

2. A reproducer, including in combination with a reproducer housing and diaphragm associated therewith, of dampening means within said housing and spaced from said 80 diaphragm, said dampening means including a piece of material presenting two opposed sections of a circle joined at the center, each of said sections being substantially 85 quadrants of a circle.

3. A reproducer, including in combination with a reproducer housing and diaphragm associated therewith, of dampening means within said housing and spaced from said diaphragm, said dampening means including a piece of material presenting two opposed sections of a circle joined at the center, each of said sections being substantially 90 quadrants of a circle, the arcuate edges of said sections engaging the inner face of said 95 reproducer housing.

4. A reproducer, including in combination with a reproducer housing and diaphragm associated therewith, of dampening means within said housing and spaced from said 100 diaphragm, said dampening means including a piece of material presenting two opposed sections of a circle joined at the center, each of said sections being substantially quadrants of a circle, the arcuate edges of said sections 105 engaging the inner face of said reproducer housing, the center of said piece of material being depressed.

5. A dampener for reproducers, including a piece of material presenting two opposed 110 sections, of a circle joined at the center, each of said sections being substantially quadrants of a circle, said dampening means being adapted to be positioned within a reproducer housing, and spaced from the diaphragm of said reproducer, the arcuate edges 115 of the sections of said dampening means engaging the inner face of said reproducer housing.

WILLIAM EDWARDS HUNT.
